UNITED STATES PATENT OFFICE.

ADOLF MESSER, OF FRANKFORT-ON-THE-MAIN, GERMANY.

ACETYLENE GENERATOR.

Application filed August 29, 1921, Serial No. 496,765, and in Germany September 12, 1916.

(GRANTED UNDER THE PROVISIONS OF THE ACT OF MARCH 3, 1921, 41 STAT. L., 1313.)

In acetylene generators with a drop lever released through the intermediary of an ascending and descending collector bell and operating the feeding device the required part of the feeding material is made to drop 5 into the generating water all at the same time. As this quantity of carbide is rather considerable in large acetylene generators there will be produced suddenly higher pressures in the generator than the admissible 10 pressure whereby disturbances of service might be caused. With a view to avoid this inconvenience it has already been proposed to drive the feeding devices for large generators by electric motors, transmissions or 15 the like, having devices for the throwing in and out of gear which are operated from the descending and ascending collector bell.

This invention has for its object to simplify such devices by using a regulating device without individual movement which regulates the sudden dropping of the carbide to be decomposed at every period in such a manner that it acts gradually within 20 a time limit which can be accurately determined. The principal characteristic feature of the improved speed regulating device consists in a braking device opposing the sudden release of feeding material, for instance in 25 a brake which controls the supply of carbide.

In order that the invention may be clearly understood, I shall proceed to describe the same with regard to the only figure of the 30 accompanying drawing.

In the top part of a gas generator *a* a feed drum *g* is fixed upon a shaft *r* revolvably mounted in the walls of said top part. The feed drum is divided into cells and fed with carbide from a hopper *f*. The pointed end 35 of a weighted lever *b* engages with a ratchet *m* fixed upon said shaft *r*, the lever *b* resting on the one hand upon a support *k* arranged upon the wall of the generator *a* and on the other hand upon a collar *i* of a cable *s* which 40 is attached to the collector bell of the gas holder not shown on the drawing. Upon shaft *r* a toothed wheel *n* is keyed which 45 operates with a smaller toothed wheel *n'*

which serves as crank disk for the connecting rod drive *o*, *p* of a pneumatic or hydraulic brake *e*, the valves *d* of which permit of adjusting the degree of compression and consequently of the revolving speed. 50

The device operates as follows:— 55

When the collector bell of the gas holder, not shown on the drawing, descends it pulls the cable *s* the collar *i* of which makes the weighted lever *b* pivot around its support *k*. The lever engaging with the ratchet *m* revolves this ratchet and through the same the feed drum *g*. At the same time the toothed wheel *n* keyed upon the shaft *r* of the drum is rotated and drives the toothed wheel *n'*, so that the connecting rod drive *o*, *p* is operated. The angle formed by the rods *o* and *p* becomes greater. The piston rod is pulled 60 out and the air in cylinder *e* is compressed. The revolving speed of driving gear *m*, *n*, *n'* is thus braked and the feed drum can revolve 65 only slowly under the action of the carbide contained in it. When the collector bell of the gas holder ascends again the cable gets slack, lever *b* is lowered but does not operate its ratchet *m* held by a pawl, the pressure of the air in cylinder *e* being equilibrated by the outflow through the valves *d*. 70

The speed produced by the transmission of the driving gear *n*, *n'* overcomes the influence of the dead point position so that the 75 braking action is always ensured. 80

I claim:

A speed regulating device for carbide feeders for acetylene generators comprising in combination with a carbide feeding hopper a 85 drum beneath said hopper, a weighted lever adapted to be raised from a device raised and lowered by the gas pressure in the gas reservoir, a ratchet upon the shaft of said drum driven by said weighted lever, a brake 90 cylinder outside the generator, a piston in said brake cylinder and an intermediary gear between the drum and the piston of the brake cylinder designed to regulate the revolving speed of the drum. 95

In testimony whereof I affix my signature.

ADOLF MESSER.
